UNITED STATES PATENT OFFICE.

HOWARD C. THOMAS, OF NORTH ATTLEBORO, MASSACHUSETTS.

DESK NOVELTY.

Application filed July 16, 1921. Serial No. 485,311.

To all whom it may concern:

Be it known that I, HOWARD C. THOMAS, a citizen of the United States, residing at North Attleboro, in the county of Bristol and State of Massachusetts, have invented new and useful Improvements in Desk Novelties, of which the following is a specification.

This invention relates to calendars and has for an object the provision of an article which is both useful and ornamental in that it embodies a calendar, a paper weight and a desk ornament.

Another object of the invention is the provision of a device of the above character, which may be manufactured at a cost which will permit of its use as an advertising novelty.

With the above and other objects in view, the invention further includes the following novel features and details of construction, to be hereinafter more fully described, illustrated in the accompanying drawings and pointed out in the appended claims.

25 In the drawings:—

Figure 1 is a front elevation of the invention.

Figure 2 is a side elevation of the same showing a portion of the frame broken away 30 to illustrate the means for holding the spherical member in position.

Figure 3 is a top plan view.

Referring in detail to the drawings, where-in like characters of reference denote corresponding parts, the reference character 10 indicates a frame which is of circular formation, the said frame being supported upon a standard 11 which rises from a base 12. This base is comparatively heavy and relatively broad, to form a firm support for the frame and to also provide a weight for papers.

Removably positioned within the frame 10 is a spherical member 13 which may be formed of any suitable material. The said member fitting comparatively snug within the frame, whose lower portion is widened as at 14 to provide a seat for the member 13. This member is provided upon its outer surface with suitable indicia representing the months and the days of the month so as to provide a calendar. The calendar includes 12 months of the year which are so arranged upon the spherical member 13 as 55 to permit them to be singly brought into

position beneath a pointer 15. This pointer is provided with side wings 16 so as to cover certain months of the year, leaving only two months exposed with the current month positioned beneath the pointer 15. The 60 spherical member 13 may be so arranged that the pointer will indicate the current month, or it may be arranged to indicate the particular day of the month and the spherical member adjusted each day. 65

The spherical member 13 is removably and adjustably held within the frame 10 by means of a set screw 16, the latter extending through the frame 10 and bearing against the spherical member. This screw 70 16 also serves as an aid in holding the pointer in position upon the frame.

The invention is susceptible of various changes in its form, proportions and minor details of construction and the right is here- 75 in reserved to make such changes as properly fall within the scope of the appended claims.

Having described the invention what is claimed is:—

1. A desk appliance comprising a supporting base adapted to serve as a paper weight, a ring frame carried by the base, a spherical member adjustable in the frame and having calendar indicia marked thereon and a pointer carried by the frame. 80

2. A desk appliance comprising a frame in the form of a vertically disposed ring having the lower end portion widened to provide a seat, a spherical member adjustable on said seat, said spherical member having calendar indicia thereon and a pointer carried by the frame. 90

3. A desk appliance comprising a base, a spherical member adjustably supported 95 therefrom, said member having calendar indicia thereon and a pointer positioned in proximity to said member.

4. A desk appliance comprising a standard, a supporting base at the lower end of the standard, a spherical member adjustably supported at the upper end of the standard and having calendar indicia thereon and a pointer co-operating with said member. 100

5. In a desk novelty, a supporting structure including a base and a ring carried thereby, a spherical calendar member seated within the ring, means carried by said ring for holding said member to its seat and re- 110

leasable to permit adjustment of the ball inside the ring and a pointer carried by the ring for reading said calendar member.

6. In a desk novelty, a spherical calendar member, a ring embracing said member and presenting a seat at its lower portion for supporting said member and having means at its upper end for locking the members to the seat, said member being freely adjustable within the ring upon releasing the lock-

ing means, a supporting base for said ring and a pointer carried by the ring and partly covering said member, said pointer having an opening therein for exposing a portion of said member therethrough and an indicating element within the opening for reading the exposed portion of said member. 15

In testimony whereof I affix my signature.

HOWARD C. THOMAS.
